(57) **CLAIM**

The ornamental design for an electronic device with display screen and graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a view of an electronic device with display screen and graphical user interface showing a first image of a notification color palette. The claimed color in FIG. 1 is Red having a Hex Value of #DA3A3A.

FIG. 2 is a second image thereof. The claimed color in FIG. 2 is Yellow having a Hex Value of #FFDF22.

FIG. 3 is a third image thereof. The claimed color in FIG. 3 is Green having a Hex Value of #34836F; and, FIG. 4 is fourth image thereof. The claimed color in FIG. 4 is Blue Grey having a Hex Value of #5A7793.

The appearance of the graphical user interface sequentially transitions between the images shown in FIGS. 1, 2, 3, and 4. The process or period in which one image transitions to another image forms no part of the claimed design.

The even-dashed broken lines showing the electronic device with display screen and portions of the graphical user interface, including all text and icons shown outside the dot-dashed broken lines, illustrate portions of the article of manufacture. The dot-dashed broken lines illustrate the bounds of the claimed design. Text inside the dot-dashed broken lines is shown in broken lines, and forms no part of the claimed design. None of the broken lines form part of the claimed design.

1 Claim, 4 Drawing Sheets
